UNITED STATES PATENT OFFICE.

C. B. MORSE, OF RHINEBECK, NEW YORK.

PLANING-MACHINE.

Specification of Letters Patent No. 14,880, dated May 13, 1856.

To all whom it may concern:

Be it known that I, CYRUS B. MORSE, of Rhinebeck, in the county of Dutchess and State of New York, have invented a new 5 and useful Improvement in Planing-Machines; and I do hereby declare that the following is a full, clear, and exact description of the construction and operation of the same, reference being had to the annexed drawing, forming part of this specification, in which—

Figure 1 is a side elevation of the machine. Fig. 2 is a top plan view of the same. Fig. 3 is a vertical section on line $\alpha\alpha$ 15 of Fig. 2.

Similar characters of reference in the several figures denote same part of the machine.

The principal object of my invention is 20 the construction of rotary planing machines, so that very thin lumber may be dressed, without marring or cutting the face of the board. To effect this, it is indispensable that the resistance to the cutters be placed 25 as near as practicable to the cut, and that position maintained irrespective of the thickness of shaving removed, this resistance being unyielding.

In my machine, the surplus wood is 30 moved from the under surface of the board, by rotary cutters over and against which, the board is carried by ordinary feed rollers.

The cutter cylinder is hung in vibrating arms, in front of a horizontal bed, whose 35 edge is a cutting instrument, which bed is so connected by mechanism, with said arms, that the bed shall have a longitudinal motion, simultaneously with the movement of the cylinder; whereby the same relative position of the front edge of the bed, and the edges of the cutters shall be maintained, in 40 all positions of the cutting cylinder. The line plate under which the board passes, and the forward bed of the machine, are 45 hung in the aforesaid vibrating arms, so as to move with the cylinder; and the line plate is susceptible of a tilting motion upon its own journals, to accommodate it to the stuff passed under it.

50 The vibrating arms I support by cam levers carrying adjustable weights; which construction obviates the necessity for submitting the stuff to the middle portion of the cutters, which exists in other machines 55 of this character.

The details of the construction and op-

eration of my machine, will be understood from the following description and reference to the drawings.

A is the frame of the machine, B B' are 60 the feed rollers, and C the cutter cylinder. This cylinder is supported by the arms $a a$, on the outside of main frame A, and attached thereto by bolts b , about which said arms are movable. These arms are also connected with the main frame by the rocking levers C, which are attached to the frame A by bolts d , and each to its respective arm a , by a bolt e . The upper arm f of each of these levers, is attached by bolt i , to the end 70 of bed D; so that when the vibratory arms $a a$ are moved about bolts b , the levers C C will give motion to the bed D.

The bed D rests in slots g of main frame and is movable therein simultaneously with 75 the motion of the vibrating arms $a a$, as above set forth. The front of this bed is a cutting instrument, as shown at l , Figs. 1 and 3, under which the cutters m pass, as the cut is made, with the effect hereafter to 80 be set forth.

In front of the cylinder C is a roller E supported in vibrating arms a , whose upper element receives the board after passing the cutter cylinder. This constitutes what I 85 term the forward bed.

The line plate F is hung in arms a by journals n , and is capable of a tilting motion about said journals, to accommodate itself to the upper surface of the board as it 90 passes under it. The axes of this line plate and of the cutter cylinder, are elements of a cylinder whose axis is the line about which the arms $a a$ vibrate (Fig. 3).

Beneath the arms $a a$, are the cam levers 95 G, each having its fulcrum in bolt p attaching it to frame A. On each of these levers is a movable weight W, for maintaining the arms a in any required position.

Motion is given to the several parts of 100 this machine by the gearing and belting usually employed in machines of this character, and which need not be here particularized. The line plate F is adjusted vertically to the thickness of stuff to be operated upon, and the cutter cylinders adjusted to remove the requisite thickness of surplus wood from the under surface of the board, by levers G and held in the desired position by a suitable adjustment of weights 105 W, upon the long arms of said levers. Any motion given to the cutter cylinder, pro-

duces a simultaneous longitudinal movement of bed D, by rocking lever connection c of arms a and bed D, as above set forth, so as to preserve to edge l of bed D and 5 cutter edges, the same relative position, for all adjustments of the cutter cylinder.

The board is carried forward by rollers B B', without bending; and as it passes from over edge l of bed D it is met by and 10 receives the action of the cutters, directly in front of the support given by said bed. As the cut is made, any disposition to tear the stuff, is at once counteracted by the cutting edge l which severs the chip instantaneously. During the passage of the board through the machine it is kept flat upon the bed by the line plate F, the tilt of which about its own axis prevents any inequality of thickness possessed by the board, from 15 interfering with its successful operation. The support given the end of the board first receiving the cut, and the action of the cutting edge l prevents effectually any injury of the leading end of the board, or 20 to any other portion thereof; and as the board leaves the machine, the leverage upon rolling bed E aids the bed D, in effecting this result for the rear end of the board. It will be seen that the board passes straight, 25 through the machine, and from the connection of cylinder and bed D, no injury can result to the thinnest stuff in dressing.

I am aware that cutter cylinders revolving below the board, have been movable 30 within the bed to regulate the thickness of shaving; but as in such cases the distance between the edges of the cutters and the edge of the bed must vary with each position of the cutter cylinder, the action of 35 my machine cannot be obtained by such construction. I am also aware that line plates have been made to swing about the axis of the cutting cylinder; the effect of which is to bend the board and leave a portion of 40 the same between the feed rollers and the cutters without support. This action of the vibrating line plate is directly opposite to that of mine.

In passing boards through machines of 45 this kind, it is necessary to run them through the middle of the machine, this is found to be inconvenient, as the middle of the cutters is thus used to the ex-

clusion of the ends, and thus become dull before the ends are worn. By means 55 of my weighted levers I am enabled to pass the board so as to be planed by one end of the cutters. This I do by moving the weight upon the lever, opposite to the side on which I pass the board, into such a 60 position as will relieve the inner edge of the board from undue pressure owing to its position on one side of the middle line of the machine, and throw the pressure on the middle of the board in the same manner as though the board had been fed directly under the center of the line plate.

I do not limit myself to the precise mechanical devices herein set forth, nor to the exact combination and arrangement of the 70 same, so long as the object is obtained without changing the principle of operation.

I claim—

1. The combination of the following mechanical elements, planing cylinder C, 75 vibrating arms a a (line plate) F, beds or rests D E and weighted levers G, or their equivalents, when arranged and combined for reducing a board to an equal thickness without bending the same.

2. Making the edge l of the bed D, a cutting instrument, and giving said bed or rest, a longitudinal movement simultaneous with the swinging back or forward of the cylinder; so that the edges of the cutters on the cylinder, will preserve the same relative position with respect to the cutting edge of the bed, in all positions which the said cylinder may occupy.

3. Giving the line plate D a tilting motion about its own axis to present its flat surface to the board under all circumstances substantially as and for the purposes set forth.

4. Maintaining the pressure on the middle of the board, irrespective of the portion of the cutters to which the board is submitted, by means of the weighted levers G, operating substantially as set forth.

In testimony whereof, I have hereunto signed my name before two subscribing witnesses.

C. B. MORSE.

Witnesses:

GEO. PATTEN,

JOHN S. HOLLINGSHEAD.
